(57) **CLAIM**

The ornamental design for a display apparatus, as shown and described.

DESCRIPTION

FIG. 1 is a perspective view of a display apparatus showing our new design;

FIG. 2 is a rear elevational view thereof;

FIG. 3 is a front elevational view thereof;

FIG. 4 is a right elevational view thereof;

FIG. 5 is a left elevational view thereof;

FIG. 6 is a top plan view thereof;

FIG. 7 is a bottom plan view thereof;

FIG. 8 is a perspective view of an alternative embodiment of a display apparatus showing our new design;

FIG. 9 is a rear elevational view thereof;

FIG. 10 is a front elevational view thereof;

FIG. 11 is a left elevational view thereof;

FIG. 12 is a right elevational view thereof;

FIG. 13 is a top plan view thereof; and,

FIG. 14 is a bottom plan view thereof.

The broken line showing of the base is for illustrative purposes only and forms no part of the claimed design.

1 Claim, 14 Drawing Sheets
